(57) **CLAIM**

The ornamental design for a charger for a personal vaporizer, as shown and described.

DESCRIPTION

FIG. 1 is a top front perspective view of a charger for a personal vaporizer, according to an example;

FIG. 2 is a bottom rear perspective view thereof.

FIG. 3 is a front view thereof.

FIG. 4 is a rear view thereof.

FIG. 5 is a left view thereof.

FIG. 6 is right view thereof.

FIG. 7 is a top view thereof; and,

FIG. 8 is a bottom view thereof.

The broken lines shown in the Figures depict portions of the charger for a personal vaporizer that form no part of the claimed design.
